ILLINOIS

COLLAPSIBLE TOILET

Application filed December 5, 1929. Serial No. 411,740.

This invention relates generally to toilets, and more particularly to a portable and collapsible toilet of a character adapted for use by persons who are traveling in conveyances, such as motor vehicles, aeroplanes, etc., which are not usually provided with toilets, the predominant object of the invention being to provide a simple device of this type which, when set up in position for use, provides a durable structure well adapted for the use intended, and when collapsed is reduced to a compact unit of minimum dimensions, which will occupy very little space in the traveler's equipment or the equipment of the conveyance.

Fig. 1 is a vertical section of a collapsible toilet constructed in accordance with this invention.

Fig. 2 is an inverted plan view of the device illustrated in Fig. 1.

Fig. 3 is an enlarged cross-section on line 3—3 of Fig. 2.

Fig. 4 is a fragmentary vertical section on a reduced scale, showing more clearly the flaps of the inner container of the device.

Fig. 5 illustrates the invention in collapsed form.

In the drawings, wherein is shown for the purpose of illustration, merely, one embodiment of the invention, A designates our improved collapsible toilet which comprises a ring seat 1, preferably, though not necessarily, oval in shape as illustrated in Fig. 2. The ring seat 1 is preferably substantially U-shaped in cross-section, as shown clearly in Figs. 1 and 3, and is provided with a plurality of elements 2 which extend transversely of the annular body which provides the ring seat. The elements 2 preferably

comprise sections of tubing extended through openings formed through the down-turned portions of the ring seat, and the opposite end portions of said sections of tubing are upset or riveted over in contact with the adjacent faces of the ring seat, as indicated in Fig. 2 at 3, to securely fix said elements to said ring seat. We prefer to provide the downwardly extended portion of the ring seat 1 with ears 4 (Fig. 1) at the locations of the elements 2 so as to allow more room for the

formation of the holes in the seat ring 1 and the arrangement of the elements in said holes.

5 and 6 designate the legs or supporting elements of the collapsible toilet A, said legs being formed preferably of heavy wire, or rods, which are bent to the desired shape. The legs 5 and 6 are hingedly attached to the ring seat 1 by having the opposite upper end portions of each thereof coiled or twisted about a pair of the elements 2 which are located in diametrically opposed relation with respect to each other, as indicated at 2' in Fig. 2, and said legs are so arranged that the lower portions 5' and 6' thereof cross each other, as illustrated clearly in Fig. 2. 60

The lower portion 5' of the leg 5 at its approximate center is provided with a depression or seat 7 in which a portion 8, located at the approximate center of the portion 6' of the leg 6, seats when the legs 5 and 6 are in 70

their upright position, as illustrated in Figs. 1 and 2. The material of which the legs 5 and 6 are formed possesses sufficient resiliency to permit the portions 5' and 6' thereof to yield when said portions are brought to- 75

gether to arrange the legs in the operative upright positions, so that the portion 8 of the leg 6 may pass over the raised portions of the leg 5 at opposite sides of the depression 7 thereof and snap into said depression. When the portion 8 of the leg 6 is in place in the depression 7, as described, it is obvious that the legs 5 and 6 will be firmly and positively locked together in their upright positions and may not be moved to their collapsed po- 80

sitions without first designedly disengaging the portion 8 of the leg 6 from the depression 7 of the leg 5. 85

Supported by the ring seat 1 of the collapsible toilet A is an outer receptacle 9, which is preferably formed of fabric treated to render same waterproof. The body of the receptacle 9 is suspended within the ring seat 1, as shown in Figs. 1 and 4, and the outer edge portion of said receptacle is shaped to closely embrace said ring seat in a manner to completely cover same, as illustrated in the views referred to. To prevent the outer receptacle from being accidentally disengaged from the seat ring 1, we provide suit- 90

100

able hooks 10 which are secured to the outer edge portion of the outer receptacle 9 and embrace the lower outer edge of said seat ring 1, as illustrated most clearly in Fig. 3. Because of this arrangement the outer receptacle may be conveniently removed from the ring seat 1 when it is desired to wash same.

Located within the outer receptacle of the device is an inner container 11, which preferably is made of paper or equivalent material, treated to render same waterproof. The body portion of the inner container 11 preferably is of such shape that it will fit closely within the outer receptacle 1, and said inner container is provided with a plurality of flaps 12 at its upper marginal edge, which, when the device is in use, are bent over the ring seat 1 and extend downwardly with respect to said ring seat, as shown in Fig. 1. After use of the device, the flaps 12 of the inner container may be drawn upwardly into contact with each other, as illustrated in Fig. 4, and if desired twisted together, and the inner container may then be disposed of in any convenient manner.

When the device is not in its upright operative position, as illustrated in Fig. 1, it is collapsed so that the legs 5 and 6 assume the positions in which they are illustrated in Fig. 5. The legs 5 and 6 are moved to the inoperative or collapsed position by simply moving the portion 8 of the leg 6 out of engagement with the depression or seat 7 of the leg 5, after which said legs are moved to the horizontal positions in which they are shown in Fig. 5. The outer receptacle 9, being formed of fabric, may also be caused to assume a flat condition and therefore the device in its collapsed condition will occupy very little space and may be stored away in totally inconspicuous places until again desired for use.

While we prefer to employ an inner container 11 which is provided with flaps 12, we may if desired dispense with the use of these flaps, and we therefore do not wish to be limited to the use of an inner container provided with flaps.

We claim:

1. A device of the character described, comprising a ring seat, a receptacle supported by said ring seat, and substantially U-shaped legs hinged to said ring seat and shaped to provide a base for the device, said legs having portions which are adapted to yieldably engage each other in crossed relation and being swingable in the form of integral U-shaped units while attached to said ring seat to positions where they are substantially in the plane of the ring seat.

60 2. A device of the character described, comprising a ring seat, a receptacle supported by said ring seat, legs hinged to said ring seat and shaped to provide a base for the device, said legs having yieldable portions which are adapted to be arranged in crossed

relation, and means forming parts of said portions whereby said legs are locked together to prevent accidental displacement thereof from their operative positions, said legs being swingable in the form of integral U-shaped units while attached to said ring seat to positions where they are substantially in the plane of said ring seat.

3. A device of the character described, comprising a ring seat, a receptacle supported by said ring seat, legs hinged to said ring seat and shaped to provide a base for the device, said legs having yieldable portions which are adapted to be arranged in crossed relation and means forming parts of said portions whereby said legs are locked together to prevent accidental displacement thereof from their operative positions, said means comprising a seat formed in one of said legs in which a portion of another leg is seated and said legs being swingable in the form of integral U-shaped units while attached to said ring seat to positions where they are substantially in the plane of said ring seat.

4. A device of the character described, comprising a ring seat, a receptacle supported by said ring seat, substantially U-shaped legs hinged to said ring seat and shaped to provide a base for the device, said legs having yieldable portions which cross each other, and means whereby said legs are locked together to prevent accidental displacement thereof from their operative positions, said means comprising a seat formed in the crossing portion of one of said legs in which a portion of the crossing portion of another leg seats and said legs being swingable in the form of integral U-shaped units while attached to said ring seat to positions where they are substantially in the plane of said ring seat.

5. A device of the character described, comprising a ring seat, a receptacle supported by said ring seat, substantially U-shaped legs hinged to said ring seat and shaped to provide a base for the device, said legs having yieldable portions which cross each other, means whereby said legs are locked together to prevent accidental displacement thereof from their operative positions, said means comprising a seat formed in the crossing portion of one of said legs in which a portion of the crossing portion of another leg seats, and fastening devices whereby said receptacle is secured to said ring seat, said legs being swingable in the form of integral U-shaped units while attached to said ring seat to positions where they are substantially in the plane of said ring seat.

6. A device of the character described, comprising a support, an outer receptacle supported by said support, an inner container of paper or like material disposed within said outer receptacle, and flaps on said inner container whereby same may be conveniently

handled, said support comprising a ring seat, substantially U-shaped legs hingedly attached to said ring seat and shaped to provide a base for the device, said legs having yieldable portions which cross each other, and means comprising a seat formed in the crossing portion of one of said legs in which a portion of the crossing portion of another leg seats whereby said legs are locked together to prevent accidental displacement of said legs from their operative positions, said legs being swingable in the form of integral U-shaped units while attached to said ring seat to positions where they are substantially in the plane of said ring seat.

In testimony that we claim the foregoing we hereunto affix our signatures.

OLIVER C. K. HUTCHINSON.
